CAMPAIGN RIBBON BADGE ASSEMBLY

Ahner A. Racburn, New York, N. Y.

Application April 5, 1949, Serial No. 85,513

2 Claims. (Cl. 46—1.6)

1

This invention relates to a structurally and functionally improved mounting and especially a mounting for campaign ribbons and similar decorations.

The present application is a continuation in part of my earlier application for United States Letters Patent filed on April 3, 1945, and identified under Serial Number 586,323.

It is an object of the invention to furnish a mounting of this type which may readily be assembled by the clerk of a store selling such mountings, the consumer or by an equally unskilled person; such assembly being achieved in accordance with the wishes of the customer and without it being necessary to have the order filled by the manufacturer of the unit.

A further object is that of providing a campaign ribbon mounting in which the several parts will remain in properly assembled condition without any probability of accidental displacement of these parts occurring. At the same time it will be practicable for the user to deliberately effect a disassembly and re-assembly of the parts without the use of any special tools should this appear to be necessary or desirable at a subsequent date.

Still another object is that of furnishing a unit of this type which will include relatively few parts each individually simple and rugged in construction and capable of manufacture by automatic machines and methods; such parts when so assembled cooperating to furnish a device having a long useful life.

With these and other objects in mind reference is had to the attached sheet of drawings illustrating practical embodiments of the invention and in which:

Fig. 1 is a perspective view of a mounting in partially assembled condition;

Fig. 2 is a similar view of the mounting bar;

Fig. 3 is a perspective view of a ribbon mounting element with portions of the ribbon broken away to disclose underlying construction;

Fig. 4 is a similar view of that element with the ribbon removed therefrom;

Fig. 5 is a view similar to Fig. 4 but showing the inner face of the element;

Fig. 6 is a transverse sectional view taken along the lines 6—6 and in the direction of the arrows as indicated in Fig. 1;

2

Fig. 7 is a view in slightly enlarged scale similar to Fig. 6, but illustrating an alternative form of construction; and

Fig. 8 is a perspective view of the ribbon mounting element as shown in Fig. 7 and with portions of its body broken away to disclose underlying construction.

Referring primarily to Figs. 1 to 6, the numeral 10 indicates the body of a bar which is preferably formed of a bendable metal. This bar may be formed with slots 11 and be provided with pins 12 adjacent its ends; the pointed ends of the latter permitting of a piercing of a blouse or shirt to which the bar is to be applied. These pins may receive retaining elements (not shown) so that the bar may be secured against dislodgement from the garment to which it is applied. At this time it is to be understood that this form of securing the mounting means is merely illustrative and that any desired structure might be associated with the bar to effect the desired results. As shown especially in Figs. 2 and 6 the opposite faces of the mounting bar are formed with transversely extending corrugations 13. These may be of a slit-like character and have their ends terminating short of the edge zone of the bar body. Accordingly, smooth edge portions 14 are provided for the purposes hereinafter brought out.

30 The ribbon mounting elements should each be of a length such that they correspond to the width of the ribbon which they are to individually mount. One such element has been shown to best advantage in Figs. 4 and 5. In Figs. 4 and 5 the numeral 15 indicates the body of this unit. This body is formed of a ductile or flexible metal and may be provided with a central longitudinally extending slot 16. The side edges of the body are extended rearwardly and inwardly as at 17 and thence rearwardly and outwardly as at 18. For the purposes of illustration the spacing of the parts has been somewhat exaggerated in the annexed drawings. In any event it will be apparent that incident to the inwardly extending portions 17 a channel is furnished such that the elements may be supported upon the bar 10. The rearwardly and outwardly turned edge portions 18 and inwardly extending portions 17 furnish channels for receiving the cut edges of a ribbon 20.

40 The latter may be folded upon itself adjacent

these edges as has been indicated at 21. Preferably the entire faces of body 15 are formed with corrugations extending in a transverse direction and throughout the zones of the inturned and outturned portions 17 and 18. These corrugations which may also be slit-like, furnish between the rear surface of part 17 and the inner face of part 18, gripping portions which firmly engage the material of the ribbon and prevent a displacement thereof after pressure has once been applied and with the ribbon in position upon the elements.

As will be understood the bodies 15 have ribbons 20 mounted thereon by employing suitable machines. A store will carry in stock a desired number of these completed ribbon mounting elements; such stock embracing a proper assortment of ribbons. The store will also carry on hand a suitable number of ribbon mounting bars. These bars may be of any desired length. As shown, they may conveniently serve to mount three ribbon elements. Obviously a greater or lesser number of such elements may be mounted according to the length of the bar which is employed. The clerk, salesman or consumer will simply slide upon the bar the selected ribbon elements, as in Fig. 3, to produce an assembly as in Fig. 1. As is apparent, the bar is received within the element incident to the T-shaped channel forming a part of the latter. In this connection it is obvious that the pins 12 or other mounting units for the bar may freely pass within the space furnished between the opposed inner ends of the inwardly extending portion 17. In so sliding the ribbon mounting elements upon the bar, no substantial difficulty will be experienced by the clerk, consumer or salesman because of the smooth edge zones 14. However, when the bar has once been assembled with the elements and the entire mounting has been disposed upon a garment, it is apparent that the surface of the latter will press against the rear edge portion of the ribbon mounting element. With such pressure the corrugations 13 of the bar will cooperate with the corrugations 19 of the element. Therefore any tendency of the latter to accidentally slide or shift longitudinally with respect to the bar will be prevented. This effect will be emphasized to even a greater extent should the entire assembly assume a slightly arcuate shape as will almost inevitably occur when the user once dons the garment. In any event, all strain to which the parts are likely to be subjected in normal use will occur in a lateral direction rather than longitudinally of the bar and thus the cooperating effect of the corrugations will be emphasized.

The same results are achievable by the structures shown in Figs. 7 and 8. In those views the reference numeral 22 indicates a mounting bar formed with rows of corrugations 23 in its opposite faces and at points spaced from its side edges. The numeral 25 indicates a ribbon mounting element which has its longitudinal side edges extended rearwardly and inwardly as at 25 and thence rearwardly and outwardly as at 26. The inner face of body 24 may be formed with rows of corrugations 27. Similar rows of corrugations 28 are formed in the inwardly extending portions 25. Final rows of corrugations 29 are preferably formed in the outwardly extending portions 26 of body 24. All of these rows are preferably substantially in line with each other and spaced a distance equal to the spacing of the rows of corrugations 23 of the mounting bar 22. As is apparent, the side edges of a ribbon 30 may be ex-

tended to project into the channels furnished by the outwardly extending portions 26 and inwardly extending portions 25. Incident to the corrugations 28 and 29, these ribbon edges will be gripped against displacement.

Anyone, in assembling the mounting, will proceed as aforescribed in connection with the structures of Figs. 1 to 6. In the event that a service man desires supplementary units associated with the mounting such as battle stars then, of course, the unit described in the earlier figures should be employed in that that assembly includes slots 11 and 16 capable of accommodating such units. Otherwise the structure shown in Figs. 7 and 8 may be slotted. Regardless of this, however, the clerk will simply select the ribbon mounting elements according to proper sequence. These will be sequentially slid onto the mounting bar 22. Such sliding action will not be difficult because of the smooth surfaces intervening the corrugations 23 and the outer side edges of the mounting bar. However, when the assembly is once applied to the wearer's garment then the corrugations 23 upon the opposite faces of the mounting bar will cooperate with the corrugations 27 and 28 of the ribbon mounting elements. Upon such cooperation occurring, accidental displacement of the parts will be prevented.

Thus, among others, the several objects of the invention as specifically aforesigned are achieved. Obviously numerous changes in construction and rearrangement of the parts might be resorted to without departing from the spirit of the invention as defined by the claims.

I claim:

1. A campaign ribbon badge mounting including in combination a substantially flat bar, a ribbon-supporting element comprising a substantially flat body presenting inner and outer faces and longitudinal edge portions integral with and inturned with respect to and spaced from the inner face of said body to provide a T-shaped channel to slidably receive said bar, such longitudinal edge portions being continued in the form of out-turned terminal portions such that channels are provided between said inturned and out-turned portions, a ribbon extending across said body and having its side edges disposed within said latter channels, the surfaces of such portions being corrugated to provide a gripping structure to retain between them such ribbon and the surface of such bar adjacent the corrugations formed in the inturned edge portions of the element being formed with cooperating corrugations, whereby said element will have its movements over said bar restrained in a manner such that substantial force must be applied to slide said element over the bar mounting the same.
2. A campaign ribbon badge mounting including in combination a substantially flat bar, a ribbon-supporting element comprising a substantially flat body presenting inner and outer faces and longitudinal edge portions integral with and inturned with respect to and spaced from the inner face of said body to provide a T-shaped channel to slidably receive said bar, such longitudinal edge portions being continued in the form of out-turned terminal portions such that channels are provided between said inturned and out-turned portions, a ribbon extending across said body and having its side edges disposed within said latter channels, the surfaces of said element being formed with transverse corrugations extending throughout the out-turned and inturned edge

portions and across the body of the same, the corrugations of such portions providing a gripping structure to retain therebetween such side edges of the ribbon and the opposite faces of said bar being formed with corrugations cooperating with the corrugations formed in the body and inturned edge portions of such element whereby said element will have its movements over said bar restrained in a manner such that substantial force must be applied to slide said element over the bar mounting the same.
